UNITED STATES PATENT OFFICE.

CHRISTIAN WILLIAM MEINECKE, OF JERSEY CITY, NEW JERSEY.

DESIGN FOR A NIPPLE.

SPECIFICATION forming part of Design No. 31,305, dated August 1, 1899.

Application filed June 21, 1899. Serial No. 721,383. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for a Nipple, of which the following is a specification.

This design has for its object to provide a novel nursing-nipple; and it consists of a globular head, a neck, a bottom bead, and a bulged body uniformly curved outward from the neck and inward to the bottom bead.

The design is illustrated by the accompanying drawings, in which—

Figure 1 is a vertical sectional view of the nipple. Fig. 2 is a top plan view, and Fig. 3 is a perspective view of the same.

In the drawings the numeral 4 indicates the globular head; 3, the neck; 1, the bottom bead, and 2 the bulged body uniformly curved outward from the neck and inward to the bead.

The design provides a novel nursing-nipple which presents a characteristic and distinguishing appearance to the eye.

What I claim is—

The design for the nursing-nipple shown and described.

In testimony whereof I have hereunto set my hand in the presence of two subscribing witnesses.

CHRISTIAN WILLIAM MEINECKE.
